ROSARY

Walter E. Sloan, 1035 E. Grandview Blvd., Erie, Pa.

Filed Mar. 2, 1964, Ser. No. 78,831

Term of patent 14 years

(Cl. D45—16)

FIG. 2

FIG. 1 is a front elevational view of a rosary showing my new design with the blades in open position; and

FIG. 2 is a side elevational view of the crucifix on a reduced scale showing the blades in closed position.

The backs of the blades, crucifix, and medal are substantially plain and unornamented.

I claim:

The ornamental design for a rosary, as shown and described.
